L. B. SIMONSON

ADJUSTABLE STAND FOR HAIR WAVING APPARATUS

Filed July 13, 1923

UNITED STATES PATENT OFFICE.

LEO B. SIMONSON, OF NEW YORK, N. Y.

ADJUSTABLE STAND FOR HAIR-WAVING APPARATUS.

Application filed July 18, 1923. Serial No. 651,281.

To all whom it may concern:

Be it known that I, LEO B. SIMONSON, a citizen of the United States, residing at New York, in the county of New York and State 5 of New York, have invented certain new and useful Improvements in Adjustable Stands for Hair-Waving Apparatus, of which the following is a specification.

This invention relates to portable hair 10 waving machines such as are in use in hair dressing establishments for imparting a permanent wave to the hair, the invention having for an object the provision of a novel and improved type of portable hair waving 15 machine characterized by simplicity of construction and ease of operation.

For further comprehension of the invention, and of the objects and advantages thereof, reference will be had to the following description and accompanying drawings, and to the appended claims in which the various novel features of the invention are more particularly set forth.

Fig. 1 of the drawings is a side elevation 25 with parts in vertical section of my improved portable hairwaving machine.

Fig. 2 is a plan view of the head thereof.

Fig. 3 is a like view but showing a modified form of head.

Fig. 4 is a fragmentary vertical sectional view of the supporting post, showing particularly the means for adjusting the counterweight.

Fig. 5 is a fragmentary elevational view 35 of the supporting post, this view being taken at right angles to Fig. 4.

Fig. 6 is a horizontal sectional view taken on the line 6—6 of Fig. 1.

Referring now to the drawings, my improved machine comprises a base 10 which may be mounted on castor rollers 11 to facilitate moving the machine about the establishment. Upon this base is fixed a tubular member 12 which forms the lower section 40 of a telescopic post for supporting the head that carries the electrically heated curlers. The upper section of this post is in the form of a tubular member 13 of smaller size than the member 12 and fitting 45 at its lower end into the latter.

On the upper end of this top post section is fixed the head 15 which carries the curlers. This head may be in the form of a rectangular frame as shown in Fig. 2 or it may 55 be of oval shape as shown in Fig. 3 and the connection to the post is made at one side of

the head so that the latter will extend above the person whose hair is being waved, the latter being seated in a chair such as indicated at C. Depending from the head are 60 the usual curling elements 16 which are electrically heated in the ordinary manner, the current being supplied through a cable 17 which leads into one side of the head. The head 15 carries a suitable number of small 65 counterweights, indicated at 19, for the curlers 16.

The top post section 13 is adapted to be adjusted vertically to bring the head 15 into proper relation to the head of the person 70 sitting in the chair C, and to this end an annular counterweight 21 surrounds the lower post section 12 and has connected thereto the ropes 22 which lead upwardly 75 therefrom and pass around pulleys 23 mounted in suitable slotted apertures 24 near the top of the said section, the ropes 22 leading downward in the top section 13 to connect to a cap 25 on the bottom end thereof. Vertical slots 26 are formed in the 80 sides of the top post section 13 to accommodate the pulleys 23 and to permit of the ropes entering into said top section. The engagement of the pulleys in the slots 26 also acts to prevent the top section 13 from 85 turning.

Formed in each side of the lower post section are zig-zag grooves such as 30 which, considered as a whole extend up and down said post. At the apical points of this 90 groove are pivoted the triangular fingers 31 which have resilient tailpieces 32 which engage in recesses 33 in the member 12 and normally retain the fingers in the position shown in Fig. 5. Into the grooves 30 project 95 rollers such as 36 carried on the ends of pins such as 37 which are radially slidable in the counterweight 21 and are normally pressed inward to keep the rollers 36 in engagement with the said grooves, by means of 100 expansion springs such as 38 coiled around the pins. Pivoted as at 39 to the outer ends of these pins 37 are handles 40 having cam extensions 41 which normally lie along the face of the counterweight. The counterweight 21 may slightly overbalance the weight of the head 15 and when the latter is to be lowered the counterweight is grasped and given an oscillatory movement on the post section 12, causing the rollers 36 to ride 105 up the grooves 30 and so raise the weight and allow the head to drop to the desired 110

position. As the rollers move along the grooves 30 they raise the fingers 31 which drop behind them to form a support as the counterweight oscillates in an opposite direction.

When the head 15 is to be raised the handles 40 are swung to cause the cams 41 to bear on the sides of the counterweight 21 and pull the pins 37 outward, withdrawing the rollers 36 from the grooves 30, and allowing the counterweight to descend and raise the head 15, a collar 45 being fixed on the post section 12 to limit the downward movement of the counterweight.

15 As will be apparent from the above description, I have provided a simple and convenient form of portable hair waving machine of simple construction and capable of easy operation.

20 Having thus described my invention what I claim as new and desire to protect by Letters Patent of the United States is as follows:

25 1. In a portable hair waving machine, a base, a post made up of upper and lower elements, the upper element telescoping into the lower one, a counterweight in the form of a ring surrounding the lower post section, ropes leading from said counterweight to 30 connect the upper post section, said lower post section being formed with zig-zag grooves extending up the sides thereof, and pins carried by the counterweight adapted to engage in the said grooves.

35 2. In a portable hair waving machine, a

base, a post made up of upper and lower elements, the upper element telescoping into the lower one, a counterweight in the form of a ring surrounding the lower post section, ropes leading from said counterweight to 40 connect to the upper post section, said lower post section being formed with zig-zag grooves extending up the sides thereof, and pins carried by the counterweight adapted to engage in the said grooves, springs urging said pins into the said grooves, and means for withdrawing said pins from the said grooves.

3. In a portable hair waving machine, a base, a post made up of upper and lower 50 elements, the upper element telescoping into the lower one, a counterweight in the form of a ring surrounding the lower post section, ropes leading from said counterweight to connect to the upper post section, said lower 55 post section being formed with zig-zag grooves extending up the sides thereof, and pins carried by the counterweight adapted to engage in the said grooves, springs urging said pins into the said grooves, and means for withdrawing said pins from the 60 said grooves, said means comprising handle elements pivotally attached to the said pins and having cam elements formed thereon adapted to bear on the face of the said counterweight when the handles are swung in one direction.

In testimony whereof I have affixed my signature.

LEO B. SIMONSON.
